MOTION CONVERTING MECHANISM

Alfred A. Bamberger, Flushing, N. Y., assignor to
Speedo Manufacturing Co., Inc., New York,
N. Y.

Application June 8, 1946, Serial No. 675,362

2 Claims. (Cl. 74—44)

1

This invention relates to reciprocating instruments. It is particularly directed to a mechanical dental or jeweler's reciprocating instrument, such as a filing, burnishing, polishing, grinding, sawing or like mechanical instrument.

An object of this invention is to provide an improved instrument of the character described which may be utilized in conjunction with a drill press, a lathe, or which may be connected to various types of flexible shafts so that the instrument may be held in the hand while it is operated.

Yet another object of this invention is to provide an improved instrument of the character described provided at one end with means for gripping a chuck or the like rotary drive, and at its opposite end with a chuck to grip a tool to be reciprocated, said instrument being so constructed that it may readily be held in the hand during use, or otherwise fixed so that its casing is held against rotation.

Still a further object of this invention is to provide an instrument of the character described including a rotary shaft, provided with a beveled gear, a second beveled gear rotatably mounted within said instrument and meshing with the first gear, and a reciprocating element connected to the second gear, the arrangement being such that rotation of the shaft will cause reciprocation of said element.

Still a further object of this invention is to provide a compact and durable instrument of the character described which shall be relatively inexpensive to manufacture, easy to manipulate, which shall be smooth and positive in operation, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a side elevational view of an instrument embodying the invention;

Fig. 2 is a cross-sectional view taken on line 2—2 of Fig. 1;

Fig. 3 is a cross-sectional view taken on line 3—3 of Fig. 2;

Fig. 4 is a cross-sectional view taken on line 4—4 of Fig. 3;

2

Fig. 5 is a side elevational view of a drill press with an instrument embodying the invention partially connected thereto;

Fig. 5a is a cross-sectional view taken on line 5—5a of Fig. 5;

Fig. 6 is a partial view similar to Fig. 2 and illustrating a modified construction;

Fig. 7 is a view similar to Fig. 6 and illustrating yet another modified construction;

Fig. 8 is an axial cross-sectional view of an instrument embodying the invention and illustrating a modified form thereof; and

Fig. 9 is a view similar to Fig. 8 and illustrating yet another modified form of the invention.

Referring now in detail to the drawing, 10 designates an instrument embodying the invention. The same comprises a casing 11 having a bottom wall 12, side walls 13 and tubular end portions 14 and 15. The casing 11 is open at the top and is formed with a central substantially cylindrical chamber 16. The casing tapers from the sides thereof towards the ends as shown in Figs. 1 and 2 of the drawing. The end portion 14 thereof is formed with an axial through opening 18 communicating with chamber 16 and extending to one end of the casing. Part of the through opening 18 is internally screw threaded as at 19. The end portion 15 of the casing is formed with an axial bore 20. Said casing has a flat top surface 21 as shown in Fig. 3 of the drawing. The axial bore 20 communicates with chamber 16.

Said chamber has a flat bottom wall 22 and an inner cylindrical surface 24. The side walls 13 are formed at their outer surfaces with aligned, circular recesses 25. At the center of each recess is a threaded opening 26. The bottom wall 12 is formed in surface 22 thereof with a central threaded opening 28 for the purpose hereinafter appearing.

Chamber 16 may be closed by a cover 30 lying on surface 21. The cover 30 may be attached to the casing by means of a set screw 32 passing through an opening therein and screwed into a threaded opening 33 in portion 14 of the casing.

Screwed within the threaded opening 19 is an inner externally threaded sleeve 35. The sleeve 35 is formed with an axial through bore 36. It extends beyond the casing as at 37. Attached to member 35 is an outer sleeve 40 coaxial with sleeve 35. Sleeve 40 has an end portion 41 fitted onto portion 37 of said member 35. Adjacent portion 41 is an internal collar 42 contacting the outer end of member 35. Said sleeve 40 is also formed at its outer end with an opening 44 for the purpose hereinafter appearing.

Extending through opening 36 in member 35 is an axial shaft 45. The shaft 45 extends to both sides of member 35. Attached to the inner end 46 of shaft 45 is a beveled gear 47 abutting the inner side of member 35 and projecting into the cylindrical chamber 16. Gear 47 may be pinned to the shaft or otherwise attached thereto. Pinined to shaft 45 and abutting the outer end of member 35 is a collar 49. Attached to the outer end of shaft 45 is an axial sleeve 50 located within the outer sleeve 40 and terminating short of the outer end of said inner sleeve. Said axial sleeve 50 is formed with a longitudinal slot 51 for the purpose hereinafter appearing.

The outer sleeve 40 is attached to portion 37 of member 35 by means of a set screw 40a or in any other suitable manner.

Attached to the bottom wall 12 of the casing is a screw 55. Screw 55 is formed with a shank 56 screwed within the threaded opening 28. It has a shoulder 57 contacting the upper surface 22 of bottom wall 12 of the casing. It is also formed with an enlarged head 58.

Rotatably mounted on screw 55 is a beveled gear 60 meshing with the beveled gear 47. Gear 60 is formed with an axial opening 61 to receive shoulder 57 and head 58 of screw 55. The bottom surface of gear 60 rests on the bottom walls 22. It is held on the bottom surface 22 by the screw 55 while permitting the gear to rotate. Attached to the top of gear 60 is a central bridge or hub 64 overlying the head of the screw 55. Said hub 64 is formed with an offset threaded opening 65. Screwed into said threaded opening is a pivot pin 66. Connected to said pivot pin is a link 67.

Mounted for reciprocation within the axial opening 20 of the casing is a rod 70. Rod 70 is formed with a slot 71 at one end. Fixed to the rod and traversing said slot is a pivot pin 72. The link 67 is pivoted at its opposite end to the pivot pin 72. It will now be understood that as shaft 45 is rotated, gear 47 will turn gear 60, which in turn will reciprocate member 70.

Member 70 is formed with an axial opening 74 extending to the outer end thereof. It is also formed with an externally threaded outwardly tapering portion 75. The tapered portion 75 is formed with a plurality of longitudinal slits. It will be noted that the tapered portion 75 is reduced in diameter toward its outer end. Screwed onto the tapered portion 75 is a tapered sleeve 80. Sleeve 80 is formed with an internally threaded portion 81 fitted within the outer end of opening 20 and engaging the threaded portion 75. Member 80 is formed with a head 82 at its outer end. As member 80 is rotated, it will squeeze together the slotted portions 75 to grip the shank 87 of an instrument inserted into the opening 74. When member 82 is rotated in an opposite direction, it will loosen slotted portions 75 to permit the shank of the tool to be withdrawn from the chuck.

The instrument 10 may be operated by means of a usual flexible shaft, one end of which is shown at 90. The flexible shaft 90 may be provided at one end with a connector head 91 formed with an annular groove 92 of curved cross section. Disposed about sleeve 40 is a split spring ring 93 formed with an opening 94. Within the opening 44 of sleeve 40 is a ball 95. The ball 95 projects into groove 92. It also projects into opening 94. The opening 44 has a diameter greater than the diameter of ball 95. The opening 94, however, is smaller. As

the head 91 is slipped into the sleeve, the ball 95 will open up the split sleeve 93 and permit said head to move past the ball, which permits the ball 95 to snap into the groove 92. The head 91 is attached to the casing 91a for the rotary flexible shaft 90. The head 91 is formed with an axial through opening 96a. Attached to the flexible shaft 90 is a rod 97 which passes through the axial opening 96a. The rod 96 may enter the sleeve 50 which is fixed to the gear shaft 45. On rod 97 is a rib or key 98 which enters the slot 51. It will now be understood that rotation of the flexible shaft 90 will cause rotation of shaft 45 for operating the mechanism.

15 The instrument may be attached to a usual drill press 100 for operation thereby. In such event, the sleeve 40 is removed by unscrewing the set screw 48. The usual chuck of the drill press may then be engaged with the projecting end of shaft 45 as shown in Fig. 5 of the drawing. The casing 11 may be held against rotation by means of a pair of arms 101 which may be attached as at 102 to the frame 103 of the drill press. The arms 101 may be attached to the sides of the 20 casing 11. Said arms may be provided with bosses 104 which enter the recesses 25. The said arms may be formed with through openings 106 registering with the opening 26 to receive screws 107 for attaching said arms to the casing. The 25 tool 81 is attached to the instrument and is reciprocated vertically. When the drill is operating the instrument may be lowered or raised and adjusted in position. To this end the arms 101 may be formed with slots 101a to receive the 30 attaching screws 102 which pass through the slots. The provisions of the slots permits adjustment of the arms 101 and instrument 10.

Some jewelers have flexible rotary shafts which are provided with a tapered chuck at one end. 40 To attach the instrument 10 to such a chuck, the sleeve 40 is removed. Also sleeve 35 is unscrewed together with shaft 45, collar 49, and gear 47. As shown in Fig. 6, there is then screwed into the threaded opening 19 a sleeve 37a similar to sleeve 35. Extending through the screw 37a is a shaft 110 to one end of which is attached a gear 47 similar to the gear 47 of Fig. 3. Also attached to shaft 110 is a collar 49 similar to the collar 49 in Fig. 3. The shaft 110, however, preferably extends rearwardly to greater length than shaft 45.

50 Mounted on the rear end of screw 37 is a sleeve 112. The sleeve 112 may be attached to screw 37 by means of an attaching screw 40a. Sleeve 112 has a tapered internal opening 113 to receive the usual tapered chuck on a flexible shaft. The 55 tapered chuck may enter the sleeve 112 and will grip the rear end of shaft 110 to rotate the latter. If desired, the sleeve 112 may be entirely removed so that larger chucks may be used as grip shaft 110.

60 In Fig. 8 there is shown an instrument 10a embodying the invention and illustrating a modified construction. The instrument 10a comprises a tubular casing 130 having an enlarged bore 131 at one end, a reduced intermediate bore 132, and a still further reduced bore 133 at its opposite end. Between bores 131 and 132 is a shoulder 134. Between bores 132 and 133 is a shoulder 135. Projecting into bore 131 is an inner sleeve 136 abutting shoulder 134. Casing 130 may be fixed to member 136 by a set screw 137. Member 136 has a portion 138 of reduced diameter projecting rearwardly. Received on said portion 138 is a sleeve 140. Sleeve 140 may be fixed to portion 75 138 by a set screw 141. The sleeve 140 contacts a

shoulder 142 on member 136 and it also contacts the rear end of casing 130. The inner sleeve member 136 is formed at its front end with an enlarged axial bore 143 and at its rear end with a reduced bore 144. Between said bores is a shoulder 147. Rotatable within sleeve 136 is a shaft 150. Shaft 150 has an enlarged portion 151 disposed in bore 143 and a reduced shaft portion 152 in bore portion 144. Shaft 152 projects rearwardly into sleeve 140. Sleeve 151 is formed with an inclined annular groove 153 for the purpose hereinafter appearing. On shaft portion 152 is a fixed collar 155 contacting the rear end of the inner sleeve 136. Shaft 150 may be rotated by any suitable means such as a flexible drive, a drill, a jeweler's lathe, or in any other suitable manner.

Mounted within casing 130 for reciprocation is a chuck 160. The chuck 160 has a head 161 within bore 132 and a portion 162 of reduced diameter within bore 130. Portion 161 is formed with a longitudinal external slot 163. Fixed to the casing 130 is a pin 164 projecting into the slot 163 to prevent rotation of member 160. The head 161 is formed with a socket 165 receiving the forward end of portion 151.

Fixed to the head 161 is a pin 166 projecting into slot 163 so that as shaft 150 rotates, member 150 will be reciprocated. Portion 162 of member 160 is formed at its outer end with an externally screw-threaded, outwardly and downwardly tapering portion 170. Said portion 162 is formed with an axial bore or opening 171 to receive the shank 172 of a tool to be reciprocated. The outer taper portion 170 may be formed with a plurality of longitudinal slits 170a to form a chuck for gripping the shank 172. Screwed onto portion 170 is a tightening screw 174 for causing the chuck to grip the tool. Obviously, when member 170 is loosened, the tool 172 may be removed.

In Fig. 9 there is shown an instrument 10b embodying the invention. The same comprises a tubular casing 175 formed at one end with an enlarged bore 176. It is also formed with an intermediate bore 177 and with a bore 178 of reduced diameter adjacent its forward end. Fixed within casing 175 is a sleeve member 179 having a portion 180 projecting from the casing; mounted on said portion 180 is a sleeve 181 fixed thereto by a set screw 182 or in any other suitable manner. Member 179 is formed with an enlarged bore 183 at its forward end and with a reduced bore 184 at its rear end.

Rotatably mounted within member 179 is a member 185 having a rearwardly extending shaft 186 projecting into sleeve 181. Member 185 furthermore comprises an enlarged cylindrical head 187 formed with an inclined, forward, cammed edge 188. Member 179 may be fixed to the casing 175 by a set screw 190. Mounted for reciprocation within casing 175 is a member 191. Member 191 is formed with a socket 192 partially receiving the head 187. Said socket 192 is formed with an external longitudinal slot 193. Fixed to the casing is a pin 194 projecting into said slot 193 to prevent rotation of member 191. Fixed to a wall of said socket 192 is a pin 195 contacting the cammed edge 188. Member 191 is provided with a portion 200 of somewhat reduced diameter forming a shoulder 201. Surrounding portion 200 is a coil compression spring 202 interposed between shoulder 201 and an internal shoulder 203 formed between bores 177 and 178.

Any suitable means may be provided to rotate member 185. As member 185 rotates, the

cammed edge 188 will move member 191 to the right. The spring 202 will move member 191 to the left. Thus as member 185 rotates, member 191 will be reciprocated. Member 191 may be provided at its outer end with a chuck to grip the shank 192 of a tool similar to the structure shown in Fig. 8.

If desired, the instrument may be attached to a usual jeweler's lathe. In such event the member 185 is replaced by a member 120, having a shaft portion 120a as shown in Fig. 7 of the drawing. Attached to the shaft 120a is a collar 121. The collar 121 may be pinned to shaft 120 and is tapered so as to cooperate with the chuck of a jeweler's lathe. The shaft 120 is provided with a usual key groove 123 with an annular groove 124 adjacent thereto and with a rear externally screw threaded end portion 125. With such construction, the instrument may be attached to a jeweler's lathe. The jeweler's lathe may furthermore be provided with arms 126 having bosses 127 received in recesses 127 in the side walls of the instrument casing. Said bosses are provided with central through openings 128a to receive screws 128 screwed within threaded openings 126a of said casing, at the bottom of the recesses for attaching said arms to the casing. The arms 126 may be attached to any fixed support to prevent the casing from rotating as the member 120 is rotated for operating the instrument.

It will be understood that shafts 45 or 110 may be replaced by shafts such as shaft 120a adapted to be received in a jeweler's chuck, if desired.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. Motion converting mechanism comprising a casing formed intermediate its length with a chamber open at its outer end and having an inner end wall, and side walls, there being an opening formed centrally of the inner wall, end portions of the casing being formed with longitudinally extending bores having their inner ends communicating with the said chamber in opposed relation to each other, a removable cover for the open outer end of the chamber, a beveled gear in said chamber disposed against the inner end wall thereof and formed with a center opening registering with the opening in said inner wall, and having its outer end portion enlarged and forming an annular recess, a fastener extending through the opening in said gear and received into the opening in said inner wall, and having a head at its outer end countersunk in said recess, said screw rotatably mounting said gear and having its head flush with the outer surface of the gear, a block detachably secured against the outer surface of said gear and covering said head and constituting a hub for the gear, a drive shaft rotatably mounted through the bore of one end portion of said casing and at its inner end carrying a beveled pinion meshing with the beveled gear, a rod slidably longi-

itudinally through the bore in the other end portion of the casing, a link pivoted to the inner end of said rod and overlapping said hub, and a pin carried by and projecting outwardly from said hub in eccentric relation thereto, the outer end of said link being formed with an opening through which said pin on the hub passes and being thereby pivotally connected with the hub and serving to impart longitudinal reciprocating motion to said rod during the rotation of the beveled gear and the hub block.

2. Motion converting mechanism comprising a casing formed intermediate its length with a chamber open at its outer end and having an inner end wall, and side walls, there being a threaded opening formed centrally of the inner wall, end portions of the casing being formed with longitudinally extending bores having their inner ends communicating with the said chamber in opposed relation to each other, a removable cover for the open outer end of the chamber, a beveled gear in said chamber disposed against the inner end wall thereof and formed with a center opening registering with the threaded opening and having its outer end portion enlarged and forming an annular recess, a screw extending through the opening in said gear and screwed into the threaded opening and having a head at its outer end countersunk in said recess, said screw rotatably mounting said gear and having its head flush with the outer surface of the gear, a block detachably secured against the outer surface of said gear and covering said screw and constituting a hub for the gear, a drive shaft rotatably mounted through the bore 35

of one end portion of said casing and at its inner end carrying a beveled pinion meshing with the beveled gear, a rod slidable longitudinally through the bore in the other end portion of the casing, a link pivoted to the inner end of said rod and overlapping said hub, and a screw carried by and projecting outwardly from said hub in eccentric relation thereto, the outer end of said link being formed with an opening through which the screw on the hub passes and being thereby pivotally connected with the hub and serving to impart longitudinal reciprocating motion to said rod during the rotation of the beveled gear and the hub block.

ALFRED A. BAMBERGER.
